W. P. ANDRICK

TELEPHONE SYSTEM

Filed March 18, 1922

Inventor
Wallace P. Andrick
by *W. C. Beatty, Atty.*

UNITED STATES PATENT OFFICE.

WALLACE P. ANDRICK, OF HOHOKUS, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed March 18, 1922. Serial No. 544,733.

To all whom it may concern:

Be it known that I, WALLACE P. ANDRICK, a citizen of the United States, residing at Hohokus, in the county of Bergen, State of 5 New Jersey, have invented certain new and useful Improvements in a Telephone System, of which the following is a full, clear, concise, and exact description.

This invention relates to a telephone system and particularly to a circuit arrangement for such a system wherein one of a plurality of telephone substations may be connected to a common line to the exclusion of other stations. An instance of this kind 10 occurs in systems in which a particular substation of a group is given sole use of a trunk line leading to a central office during connection therewith so as to insure secrecy of conversation.

20 In some systems of this nature, a key is employed at the particular or preferred substation which, when actuated, excludes all other substations from the trunk line. It has been found that if the key is accidentally or otherwise actuated when the preferred substation is not using the trunk, all other substations will be excluded from the trunk.

It is therefore an object of this invention 30 to prevent a main station in a system of this kind from disconnecting other stations from a line except when the main station is telephonically connected to the line.

A feature of the invention consists in the 35 provision of a circuit arrangement such that the depression of the key at the main or preferred substation effects the disconnection of the remaining stations associated with the trunk line only when the receiver at the preferred substation is removed from the switch hook.

In the accompanying drawing, the invention 45 is illustrated diagrammatically in its application to an intercommunicating system, only such portions being shown as are necessary to its understanding.

A plurality of intercommunicating substations A, C and D, of which only one is illustrated in detail at A, are joined by a 50 trunk line to a battery B at a central station. The battery B is shown as being fed through the left-hand winding of a repeating coil 20 which may be in a cord circuit of a well-known repeating coil type. The 55 substations C and D of the system have

communication with the trunk by way of the leads L' through the back contacts 10 of a relay 15. The winding of relay 15 receives current through a local circuit including battery B' of the intercommunicating system and a non-locking manually operable switch K at the preferred substation, when the contacts of the relay 12 in circuit with the preferred substation A are closed. A locking circuit for the relay 15 is closed through its own contacts when it and relay 12 are energized.

If the subscriber at station A wishes to converse with a party at the main exchange without permitting access of the other stations to the line L, he will remove the receiver from the switch hook and, if no conversation is heard on the line, operate the key K. It will be understood that in some systems to which this invention is applicable, the trunk line L will be connected to a line relay (not shown) at the central office having battery and ground connected thereto in a manner well known in the art. The removal of the receiver from the switch hook 70 A will cause a line lamp (not shown) to light at the central office in the well-known manner and the operator may insert the answering end of a cord circuit into the jack (not shown) of the line thereby connecting the battery B in circuit with the station A. The removal of the receiver from the switch hook at station A causes current 75 from the battery B at the central office to flow over the trunk line L through the station A thereby causing the energization of relay 12. Relay 12 in operating closes its contacts thereby preparing a circuit for the actuation of relay 15.

The actuation of key K then causes the energization of relay 15 over a path extending from the plus pole of battery B' through the winding of relay 15, contacts of relay 12, contacts of key K to the minus pole of the battery B'. Relay 15 in operating opens its contacts 10, 10 thereby disconnecting the stations C and D from the trunk leads L', L' and closes its contacts 14, 14 thereby connecting a buzzer 11 in circuit with the stations C and D. Relay 15 in operating also completes a locking circuit for itself independent of the key K over a path extending from the plus pole of battery B', through the winding of relay 15, contacts of relay 12, upper contacts of relay 15 to the minus pole of battery B'. 100 105 110

If, during the time that station A is conversing over the trunk line L with a party at the central office, another station of the group, such as C or D, attempts to make a call over the trunk line L, the buzzer 11 will be operated to inform such station that the trunk line L is busy. The circuit for operating buzzer 11 includes the loop of the calling station, such as C or D, contacts 14 of relay 15, battery B' and contacts of buzzer 11.

At the termination of the conversation, the return of the receiver to its switch hook at station A causes the release of relay 12 and relay 12 in releasing opens the locking circuit for relay 15, which in releasing restores the circuit to normal. The system is then in condition for a call from any of the substations.

It will be obvious from the preceding description that if the preferred station is connected to the trunk on either incoming or outgoing connections, all other stations may be barred from the trunk by momentarily depressing the non-locking key. It will also be noted that an accidental or other actuation of the key K, when the receiver of the station A is not removed from the switch hook, will not cause disconnection of stations, such as C and D, from the trunk line L since the circuit for relay 15 can only be completed when relay 12 is energized and its contacts are closed.

What is claimed is:

1. The combination with a plurality of telephone substations and a line therefor, of a relay for governing the connection of certain of the substations to the line, a relay included in the line energized by one of said substations, and means situated at the said one substation for controlling said relay only when said line relay is energized.

2. A plurality of associated telephone stations, a line for connecting said stations to another station and a plurality of electromechanisms individual to one of the associated stations and being adapted to vary the connection of such stations to the line, one of the electromechanisms being energized over the line and the other locally, said other mechanism being capable of being operated only when said first mentioned electromechanism is energized.

3. In a telephone system, the combination with a plurality of substations, of a line for connecting said substations to another station, a plurality of electromechanisms for disconnecting from the line all but a particular substation, and a switchhook at said particular substation for controlling the initial energization of one of the electromechanisms by current locally, another of the electromechanisms continuing such energization and being energized only when said particular substation is in use.

4. In a telephone system, the combination with a plurality of substations, of a line normally connected to one of said substations for connecting one of said substations to another station, a plurality of electromechanisms for varying the connection of the substations to the line, means at the substation for controlling the action of said electromechanisms only when the receiver of the substation is off the hook, and means operable when the receiver is replaced for controlling the restoration of said electromechanisms to normal.

5. In a telephone system, the combination with a plurality of substations, of a line normally connected to one of said substations for connecting one of said substations to another station, a plurality of electromechanisms for varying the connection of the substations to the line, a key at the said one substation for controlling the action of said electromechanisms only when the receiver of the substation is off the switchhook, and a switchhook at the said one substation for controlling the restoration of said electromechanisms to normal.

6. In a telephone system, the combination with a plurality of substations, of a line normally connected to one of said substations for connecting said substations to another station, a plurality of electromechanisms for varying the connection of the substations to the line, and a manually operable switch at a substation for controlling the action of one of said electromechanisms only when the receiver of the substation is off the hook, the restoration of said electromechanisms being controlled by the substation switch hook.

7. A trunk line, a preferred substation directly connected thereto, other substations, a disconnecting relay through the back contacts of which said other substations are joined to the trunk, a relay having its winding included in the trunk, and a circuit including a key at the preferred substation and a contact of said trunk relay for energizing the disconnecting relay.

8. A trunk line, a preferred substation directly connected thereto, other substations, a disconnecting relay through the back contacts of which said other substations are joined to the trunk, a relay having its winding included in the trunk, a circuit including a key at the preferred substation and a contact of said trunk relay for energizing the disconnecting relay, and a locking circuit for the disconnecting relay including the contacts of the trunk relay.

9. The combination of a plurality of telephone substations and a line therefor, of a first and a second relay governing the connections of the substations to the line, means including a switchhook for energizing the first relay, means including a key for ener-

gizing the second relay, a locking circuit for the second relay, and means for rendering the locking circuit effective only when said first relay is energized.

5 10. A trunk line, a telephone station, an electroresponsive switching device serially connected in said line, a key, and a circuit

including a contact of said key and said device to prevent the association of said telephone station with said trunk line. 10

In witness whereof, I hereunto subscribe my name this 14th day of March, A. D. 1922.

WALLACE P. ANDRICK.
